UNITED STATES PATENT OFFICE.

HARRY S. WATERMAN, OF SAN FRANCISCO, CALIFORNIA.

DESIGN FOR AN AUTO WHEEL LOCK.

60,204.

Specification for Design.

Patented Jan. 10, 1922.

Application filed February 16, 1921. Serial No. 445,561. Term of patent 7 years.

To all whom it may concern:

Be it known that I, HARRY S. WATERMAN, a citizen of the United States, residing at the city and county of San Francisco and State of California, have invented a new, original, and ornamental Design for an Auto Wheel Lock, of which the following is a specification, reference being had to

the accompanying drawing, forming part thereof.

The figure is a perspective view of an auto wheel lock, showing my new design.

I claim:

The ornamental design for an auto wheel lock as shown.

HARRY S. WATERMAN.
